UNITED STATES PATENT OFFICE.

HOWARD N. RICHARDS, OF PITTSBURGH, PENNSYLVANIA, ASSIGNOR TO WESTINGHOUSE ELECTRIC & MANUFACTURING COMPANY, A CORPORATION OF PENNSYLVANIA.

INSULATOR.

1,393,398.

Specification of Letters Patent. Patented Oct. 11, 1921.

Application filed February 19, 1921. Serial No. 446,306.

To all whom it may concern:

Be it known that I, HOWARD N. RICHARDS, a citizen of the United States, and a resident of Pittsburgh, in the county of Allegheny and State of Pennsylvania, have invented a new and useful Improvement in Insulators, of which the following is a specification.

My invention relates to insulators and particularly to means for holding lock washers in position on insulators for supporting trolley conductors.

The object of my invention is to provide a device of the above indicated character that shall embody normally separable parts secured together as a unitary structure to facilitate shipping and manipulation.

Insulators, such as those of the cap-and-cone type for supporting trolley conductors, are usually provided with a depending stud 20 for coöperation with a trolley-conductor ear or clamp. In its final position, relative to the insulator and to the conductor, the ear or clamp must be in alinement with the conductor and in relatively tight engagement on the stud to prevent chattering and damage to the threads, caused by passing trolleys. A lock washer or similar means 25 is usually provided to take up the back-lash between the threads of the stud and the 30 ear.

It is desirable to have as few separate parts as possible, particularly small parts, to prevent loss and to facilitate shipping and mounting.

35 In practising my invention, I provide a relatively simple and inexpensive means for so mounting a normally separate lock washer on a trolley-conductor insulator as to permit the washer and the insulator to be 40 shipped as a unitary structure, thereby, precluding loss and reducing the number of mounting operations.

Figure 1 of the accompanying drawings is a view, partially in side elevation and partially in section, of a cap-and-cone insulator embodying my invention.

Fig. 2 is a bottom plan view of the device shown in Fig. 1 and

45 Figs. 3 and 4 are, respectively, bottom plan and side elevation detail views of a member embodied in my invention.

A stud 1, having a depending threaded end portion 2 and a headed end portion 3, is embedded in an insulating cap member 4

of molded material. An intermediate metal 55 ring or supporting member 5 is provided with arms 6 having end portions 7 of substantially hook shape for the reception of a guy wire (not shown). The interior perimeter or surface 8 of the ring 5 is shaped 60 to conform to a frusto-conical molded insulating member 9 having an opening 10 through which the stud 1 extends. A relatively thin metal washer 11, having laterally-projecting spaced peripheral projections 12 65 and a usual washer 13 for reinforcing the body of the washer 11, are permanently mounted by being placed in position in the insulating member 9 during the molding operation of the latter. The washers 11 and 13 are so positioned as to provide an opening or countersunk portion 14 in the member 9 for the reception of a lock washer 15. The latter is held in position by bending the projections 12 around the outer edges 75 thereof. The projections 12, being very thin and yieldable, do not interfere with the usual functioning of the lock washer.

When a trolley ear or clamp (not shown) is advanced inwardly on the stud, it is permitted sufficient adjustment along the stud, while in binding, coöperation with the lock washer, to permit it to be alined with a trolley conductor.

The device is simple and compact in construction and permits the ready replacement of the lock washer.

While I have shown and described a preferred embodiment of my invention, I desire it to be understood that modifications may 90 be made therein by those skilled in the art without departing from the spirit and scope of my invention as defined in the appended claims.

I claim as my invention:

1. In combination, two washers, one of which is provided with spaced projecting portions bent around the outer periphery of the other to hold the washers together.

2. The combination with a screw threaded 100 member, of a lock washer surrounding the same and a member disposed in proximate relation to the threaded member having a portion bent into interlocking relation with the lock washer.

3. The combination with a screw threaded member, and a lock washer thereon, of a second washer having a portion interlocking

with the lock washer to hold the latter in position.

4. The combination with a screw-threaded member and a lock washer thereon, of a relatively thin washer having a portion bent into interlocking engagement with the lock washer to hold the latter in position.

5. The combination with an insulator and a stud projecting therefrom, of a lock washer and bendable means for interlocking the insulator and stud with the lock washer.

6. The combination with an insulator and a stud projecting therefrom, of a lock washer embracing the stud adjacent to the insulator, and a member secured in proximate relation to the stud and having a portion bent into holding relation to the lock washer.

7. The combination with a trolley-conductor insulator and a stud projecting therefrom, of a lock washer surrounding the stud adjacent to the insulator and a relatively thin metal washer secured in position and disposed around the stud having a portion bent into holding relation to the lock washer.

8. The combination with a trolley-conductor insulator having a countersunk opening and a stud projecting from the opening, of a lock washer surrounding the stud adjacent to the insulator and a relatively thin metal washer secured in position in the countersunk portion of said opening and having a portion bent around a portion of the lock washer to hold the latter in position.

9. The combination with a trolley-conductor insulator having a countersunk opening and a stud projecting from the opening,

of a lock washer surrounding the stud adjacent to the insulator and a relatively thin metal washer molded in position in the countersunk portion of said opening and having edge projections bent around an edge of the lock washer to hold the latter in position.

10. The combination with a trolley-conductor insulator having a countersunk opening and a stud projecting from the opening, of a relatively thin metal washer molded in position in said opening and having spaced projections on its outer edge, a second washer for reinforcing said relatively thin washer molded in position in the countersunk portion of said opening and a lock washer disposed adjacent to said second washer, said projections being bent around the outer edges of the lock washer to hold the latter in position.

11. An insulator comprising a body of molded insulating material adapted for the reception of a bolt or stud and a lock washer on the bolt, and a member molded in position in said insulating material for holding the lock washer in position.

12. An insulator comprising a body of molded insulating material adapted for the reception of a bolt or stud and a lock washer on the bolt, and a member molded in position in said insulating material and having a movable portion for holding the lock washer in position.

In testimony whereof, I have hereunto subscribed my name this 15th day of February, 1921.

HOWARD N. RICHARDS.
